Fig. 3.

Fig. 4.

In the drawings:

Fig. 1 is a front elevation view of a vacuum cleaner or similar article embodying my new design.

Fig. 2 is a side elevation view of the vacuum cleaner looking in the direction of the arrow in Fig. 1.

Fig. 3 is a perspective view of the vacuum cleaner showing the front, top and side opposite to the side shown in Fig. 2.

Fig. 4 is a fragmentary bottom elevation view of the vacuum cleaner with portions cut away on approximately line 4-4 of Fig. 2 and shown in section to more clearly illustrate the design.

The back elevation view is substantially like the front elevation view, except for the handle and socket escutcheon, which exists only on the front of the vacuum cleaner. The dominant features of the design reside in the portions shown in full lines.

I claim:

The ornamental design for a vacuum cleaner or similar article, substantially as shown and described.
